(57) **CLAIM**

The ornamental design for an intraoral scanner wand, as shown and described.

DESCRIPTION

FIG. 1 is a front elevation view of an intraoral scanner wand in accordance with the present invention;

FIG. 2 is a back elevation view thereof;

FIG. 3 is a left side elevation view thereof;

FIG. 4 is a right side elevation view thereof;

FIG. 5 is an enlarged top plan view thereof;

FIG. 6 is an enlarged bottom plan view thereof;

FIG. 7 is a front perspective view thereof;

FIG. 8 is a back perspective view thereof;

FIG. 9 is a second front perspective view thereof; and,

FIG. 10 is a second perspective view thereof.

The broken lines shown in the drawings are for the purpose of illustrating portions of the intraoral scanner wand that form no part of the claimed design.
